UNITED STATES PATENT OFFICE.

JOSEPH PRICE MORRIS, OF BRIDGEPORT, CONNECTICUT, ASSIGNOR TO BARTONS BIAS NARROW FABRICS COMPANY, OF BRIDGEPORT, CONNECTICUT, A CORPORATION OF CONNECTICUT.

DESIGN FOR BIAS TRIMMING.

Application filed April 10, 1924. Serial No. 9,218. Term of patent 3½ years.

To all whom it may concern:

Be it known that I, JOSEPH PRICE MORRIS, a citizen of the United States, and a resident of Bridgeport, in the county of Fairfield and State of Connecticut, have invented a new, original, and ornamental Design for Bias Trimming, of which the following is a specification, reference being had to the accompanying drawing, forming a part thereof, and in which the figure shows a plan view of a piece of bias trimming showing my new design.

I claim:

The ornamental design for bias trimming substantially as shown.

Signed at Bridgeport in the county of Fairfield and State of Connecticut this 8th day of April, A. D. 1924.

JOSEPH PRICE MORRIS.
